2 Claims

ABSTRACT OF THE DISCLOSURE

Prefabricated bunker units are provided with alignable steel half-sections in which are secured shear-resistant inserts pressed into the wall sections of units and are formed as wedges. Concrete fill is provided between the adjacent units which also have air escape holes.

BACKGROUND OF THE INVENTION

According to an inventive concept described in a companion application, the known steel reinforced concrete sections of a bunker installation are joined by means of a floor slab to resist shearing stresses. This is effected by the provision of projecting portions which are secured to a bottom armor plate, the floor slab projecting laterally from the bunker and increasing in thickness from its edge portions towards the middle.

In order to provide a shear-resistant, gas and watertight connection of the individual sections at their parting planes, it is proposed, according to the invention, to provide oppositely anchored steel half-sections in which are mounted, transversely to the parting planes, shear-resistant inserts, pressed into the wall sections, of wedge or wedge-like design.

A further modification of the invention resides in the provision of recesses in the parting plane of the bunker sections, for receiving a quantity of poured concrete; air slots for allowing the escape of air during the pouring; an asbestos cord on both sides of the recesses and the shear-resistant inserts in the upper ends of the recesses. A penetration of heat waves into the concrete fill is thus prevented in case of a catastrophe and thus a flow of heated concrete, thereby assuring a gas and watertight connection.

The invention is illustrated in the accompanying drawing, in which:

FIG. 1 is an elevational view, partly in section, showing the connecting portions of a pair of bunkers;

FIGS. 2 and 3 are enlarged details of the construction of FIG. 1;

FIG. 4 shows a modification of the insert means and FIG. 5 is cross-section, on a horizontal plane, through a parting zone of adjacent bunker sections.

The reinforced concrete bunker sections 1 have a floor slab 6 provided with armor on their bottom faces. The floor slab 6 projects outwardly of the bunker parts and

2

increases in thickness from the outer edges towards the middle. The individual bunker sections 1 are secured to one another by bolts 8. The bunker sections 1 are provided with semi-annular recesses for the steel inserts 9, in which are embedded anchors 10. The half sections are preferably of oval shape; however, they could also be of any other shape, for example sextagonal. Shear-resistant inserts are provided in the half-sections transversely to the parting line of the bunker sections and are pressed by means of a key 12 against steel section wall.

In FIG. 4 both shear-resistant inserts are of wedge-like construction.

Recesses 13 are provided in the parting plane under the steel inserts 9, and are formed with slots 14 for the escape of air. Asbestos cord 15 is inserted on both sides of the recesses 13. The recesses 13 are filled with a concrete filler 16, which the air escapes through the slots during the pouring of the concrete.

I claim:

1. A bunker shell assembly comprising at least a pair of adjacent independent bunker shells secured to one another, each of said bunker shells having at least one pair of vertically extending spaced walls of rectangular cross-section defining an opening in each of said bunker shells, the walls of one of said bunker shells aligned with the respective walls of the other bunker shell, said walls having oppositely disposed semi-annular recesses, semi-annular steel inserts anchored in said semi-annular recesses, a pair of shear-resistant inserts received in each pair of adjacent steel inserts and bolts extending through said oppositely disposed wall sections, respectively, said shear-resistant inserts being of wedge-like cross-section and a wedge key inserted between said shear-resistant inserts.
2. A bunker assembly as claimed in claim 1, further provided with concrete filler recesses under said steel inserts, concrete filler in said concrete filler recesses, said concrete filler recesses having slots for the escape of air, and asbestos cord inserted between said adjacent walls of each bunker shells on both sides of said semi-annular recesses.
